SURFACE WAVE GENERATOR

David L. Coursen, Newark, Del., assignor to E. I. du Pont de Nemours and Company, Wilmington, Del., a corporation of Delaware

Filed July 1, 1958, Ser. No. 745,873

3 Claims. (Cl. 102—22)

The present invention relates to a novel high-explosive device wherein the natural detonation front is distorted. More particularly, the present invention relates to a surface wave generator, i.e., a high-explosive device wherein a detonation front generated at one point is made to arrive simultaneously at a plurality of points on a desired surface.

When a homogeneous mass of a high explosive is initiated at one point, the resultant detonation front proceeds outwardly from the point of initiation at uniform velocity in all directions. For example, in the case in which a spherical charge of a high explosive is initiated at its center, the detonation front travels uniformly through the charge as an expanding sphere, the front eventually arriving simultaneously at all points on the surface of the charge. When, however, the spherical charge is not initiated at its center but at an eccentric point such as a point near its surface, the detonation front in this second case initially constitutes an expanding sphere until the portion of the boundary nearest the point of initiation is reached. Thereafter, the front travels through the remainder of the charge as an expanding segment of a sphere, the radius of curvature of the segment at any given point in the charge being determined by the distance from the initiation point. In the third case, a nonspherical homogeneous mass of explosive, e.g. a pyramid, centrally or eccentrically initiated, the detonation front proceeds in the same manner as in the eccentrically initiated spherical charge. It is obvious that in either case 2 or case 3 the detonation front, because of its natural curvature, does not arrive simultaneously at all points on the surface of the charge but arrives at various times, depending upon the distance between each finish point and the starting, or initiation, point.

In many applications of explosives besides blasting, it is desirable to employ an explosive charge wherein the detonation front arrives simultaneously at a plurality of predetermined points on one or more surfaces of the charge. For example, U.S. Patent 2,604,042 (Cook, J. H., to Imperial Chemical Industries, Ltd., July 22, 1952) describes a method whereby a metal surface is embossed by means of a plane detonation front, i.e. a detonation front which is distorted to arrive simultaneously at a plurality of points on a surface. The explosive charge used is a composite charge consisting of several different explosives, each having a different detonation velocity. The form of the charge is such that not only a great deal of care must be taken in correlating the different detonation velocities but also a large quantity of explosive material must be incorporated into the charge. This large amount of explosive increases the cost of the unit and, moreover, frequently results in the destruction of the adjacent metal surface due to the brisance of the explosive which is present in such large quantities. Obviously, the provision of a charge capable of producing the desired distortion of the detonation front and yet consisting of an inherently smaller quantity of explosive material is of great value in this application. Moreover, the use of such a surface wave generator is exceedingly valuable in basic investigations of explosive phenomena. For example, in a fundamental study of the subjection of objects such as metal plates to explosive superpressures, i.e. the exceedingly high pressures

2

of short duration generated by a high explosive, a determination of the effect of a plane detonation front is of interest. A prerequisite of such an investigation of course is the availability of an explosive charge which not only will generate the plane detonation front but also will not destroy the object subjected to the superpressure.

Accordingly, an object of the present invention is the provision of an explosive device wherein the detonation front generated at one point is directed to arrive simultaneously at a plurality of points on a surface. Another object of the present invention is the provision of a surface wave generator wherein the quantity of explosive is held to a minimum. A further object of the present invention is the provision of a surface wave generator in which only one explosive composition is required. A still further object of the present invention is the provision of a surface wave generator causing a minimum of damage to adjacent objects.

10 I have found that the foregoing objects may be achieved when I provide as a surface wave generator a mass of a cap-sensitive high explosive within which mass are disposed at least six inert rod-shaped barriers, the barriers defining a continuous matrix of the high explosive and delimiting a series of paths from the initiation point to each of a plurality of finish points on the base of the mass, each of the paths being of sufficient cross-sectional area to support the detonation, the shortest detonation path being equal for each initiation point-finish point route, the barriers being stacked in at least four parallel layers, the barriers in each layer being parallel, coplanar, and separated by a gap of at least 0.3 millimeter, the barriers in each layer crossing perpendicularly the barriers in the immediately adjacent layers, and 15 lying directly over the gaps between barriers in the next-to-nearest lower layer, each barrier having a cross-sectional area of at least 3 square millimeters and sufficient to prevent the propagation of the detonation through the barrier, the minimum dimension of each barrier being at least 1 millimeter, the length of the barrier in any given layer except the last layer being equal at least to

$$\frac{(2n+1-(-1)^n)}{4} w_{n-1}$$

20 wherein n is the layer number and w_{n-1} is the width of the barriers in the preceding layer, the length of the barrier in the last layer being equal at most to

$$\left(2^{\frac{[2N-1-(-1)^N]}{4}}\right) w_{N-1}$$

25 wherein N is the total number of barrier layers and w_{N-1} is the width of the barriers in the next-to-last layer, the number of barriers in any given layer except the last layer being equal to at least

$$\frac{2n+1-(-1)^n}{4}$$

30 wherein n is the layer number, the number of barriers in the last layer being equal at most to

$$2^{\frac{[2N-3-(-1)^N]}{4}}$$

35 wherein N is the total number of barrier layers.

The afore-described surface wave generator is based upon well-known principles. Namely, first, for every high-explosive composition, there is a certain minimum dimension (width or thickness), most conveniently expressed as the cross-sectional area, required to support a detonation, the detonation being found to travel midway between the edges of this minimum size area. Second, for every high explosive of given cross-sectional area, the propagation of the detonation is diverted by

the interposition in the path of the explosive train of an inert barrier of certain dimensions. Therefore, the detonation travels only along those paths between a given initiation point and a given finish point which are of sufficient cross-sectional area to support the detonation. In the absence of any inert barriers, the detonation travels directly, i.e. in a straight line, to the finish point. When barriers of sufficient dimension to interfere in the detonation propagation are provided in its path, the detonation must travel around each barrier put in its way.

Thus, it can be readily seen that the detonation can be forced to take a predetermined and desired path in a mass of explosive containing a plurality of barriers. When the barriers are of sufficient dimension to control the diversion of the detonation and are so disposed that the shortest paths from the starting (initiation) point to each of the finish points on a desired surface are equal in length, the detonation front arrives simultaneously at all the finish points on the desired surface.

In order to describe more completely the nature of the present invention, reference is made to the accompanying drawings, in which

FIGURE 1 shows a front view of one embodiment of the surface wave generator of the present invention, the embodiment being constructed in the form of a cube.

FIGURE 2 shows a front view of another embodiment of the present device, this embodiment being constructed in the form of a pyramid.

Referring now to the figures in more detail, in FIGURE 1, B represents the rod-shaped barriers which may be solid or in the form of air gaps, i.e. empty holes, E the mass of explosive constituting a continuous matrix in the device, and P_0 the initiation point. The barriers B have a dimension and arrangement such that they divert the detonation and delimit paths having the cross-sectional area of explosive required to support detonation. In this embodiment, the individual barriers of maximum width are located in the two uppermost layers, and the barriers decrease in width with increase in their number per layer.

In FIGURE 2, B, E, and P_0 are as in FIGURE 1. In this pyramidal mass of high explosive, however, all barriers are of the same width.

In both embodiments, the barriers, at least six in number and in at least four parallel layers, are arranged so that the barriers in any given layer, which barriers are parallel, coplanar, and separated by a gap, cross perpendicularly the barriers in the immediately adjacent layer or layers and lie directly over the gaps between barriers in the next-to-nearest lower layer. Although the barriers in a given layer are noncontiguous, the adjacent parallel layers may be contiguous.

In the operation of either embodiment, the mass of explosive is initiated at point P_0 by conventional initiation means, e.g. an electric blasting cap. The detonation thus generated travels through the explosive mass along the tortuous paths delimited by the barriers and arrives at the plurality of finish points on the base of the explosive mass. Since all possible shortest detonation paths between the initiation point and the finish points on the base are equal in length, the detonation front, which is traveling at uniform velocity, arrives simultaneously at every finish point on the base.

Obviously, therefore, the only critical features of the present invention are: (1) that the high explosive must be in the form of a continuous matrix, (2) that the barriers must be of sufficient cross-sectional area to prevent the propagation of the detonation through the barrier, (3) that the initiation point-finish point paths must be of sufficient cross-sectional area to support the detonation, and (4) that the shortest detonation path to the finish point on the base must be equal for each of the initiation point-finish point routes, the arrangement of the barriers satisfying the afore-discussed requirements.

By fulfillment of all the above requirements, a variety

of surface wave generators are prepared which function satisfactorily, the exact configuration employed being dependent upon such considerations as economics, the application in which the unit is to be used, and so on. For example, the FIGURE 1 embodiment may be preferred when the surface wave generator is to be used in an area of limited vertical space because it is of less height than the FIGURE 2 unit, although it requires the use of more explosive, with subsequent increase in cost, than does the FIGURE 2 embodiment. On the other hand, when space is not at a premium, the FIGURE 2 embodiment would be preferred. It must also be stated that the cost of the FIGURE 1 embodiment can be reduced somewhat by cutting off some of the explosive in the region of the uppermost layers, sufficient explosive being left, however, to cover fully the barriers. In this connection, it should be pointed out that the formation of the FIGURE 2 embodiment as a cube having an internal pyramid of barriers is feasible but in most cases undesirable, inasmuch as the additional explosive thus required would increase the cost of the unit and might damage adjacent objects.

The exact explosive composition used is not critical so long as the explosive material detonates at high velocity and can be formed into the necessary continuous matrix surrounding the barriers. Such explosives include, among others, PETN, RDX, HMX, pentolite (a PETN-TNT mixture), cyclotol (a RDX-TNT mixture), and tetrytol (a tetryl-TNT mixture). Of these explosives, the binary mixtures are preferred due to the ease with which they can be formed into the continuous matrix as for example by casting. To illustrate, the surface wave generator of the present invention may be prepared from pentolite or the like by stacking the rod-shaped barriers in the required arrangement in a mold of the proper form, heating the barriers, pouring molten pentolite over the barriers, and then cooling. If air gaps are to constitute the barriers, the solid rod-shaped barriers, acting as forms, may be removed and reused. The units may also be formed in layers, i.e. one layer of the barriers may be positioned in the form, the explosive poured over and allowed to cool, and then the next layer formed and so on. Naturally, in practice, this preparation method will give a unit having noncontiguous layers. In the stacking step, a mechanical feeding and stacking device may be used, the design of which device is within the scope of the mechanical art.

As afore-mentioned, each of the barriers must be of sufficient cross-sectional area to prevent the propagation of the detonation through the barrier. The barrier cross-sectional area naturally is thus dependent upon the specific high explosive constituting the matrix and upon the specific material of the barrier, since the barrier cross-sectional area necessary to prevent the propagation is a function not only of the explosive composition but also of the barrier material. I have determined that each of the barriers must have a cross-sectional area of at least 3 square millimeters to prevent propagation through the barrier, the minimum dimension of any barrier being at least 1 millimeter. However, inasmuch as the cross-sectional area is dependent upon the explosive composition and barrier material, the exact area is not a specific value. The length of the barriers is dependent upon the barrier width and the number of the layer containing the given barrier, as expressed by the following mathematical relationships:

$$B_N \leq \left(2 \frac{[2N-1 + (-1)^N]}{4} \right) w_{N-1} \quad (1)$$

wherein B_N is the length of the barriers in the last layer, N is the total number of barrier layers, and w_{N-1} is the width of the barriers in the next-to-last layer, and

$$B_n \geq \frac{(2n+1 - (-1)^n)}{4} w_{n-1} \quad (2)$$

wherein B_n is the length of the barriers in any given layer except the last layer, n is the number of the given layer ($n=N$), and w_{n-1} is the width of the barriers in the layer preceding the given layer. The following table lists some of the values satisfying these equations:

$n(N)$ ¹	$B_N \leq$ (Eq. 1)	$B_n \geq$ (Eq. 2)
2	$2w_1$	w_1
3	$2w_2$	$2w_2$
4	$4w_3$	$2w_3$
5	$4w_4$	$3w_4$
6	$8w_5$	$3w_5$
7	$8w_6$	$4w_6$
8	$16w_7$	$4w_7$
9	$16w_8$	$5w_8$
10	$32w_9$	$5w_9$

¹ The length of the barriers in the first layer is arbitrary.

² These values of course are eliminated by the requirements of the construction of the unit.

To achieve the desired results, at least 6 barriers in at least 4 parallel layers are required.

Mathematical expressions can be set forth limiting the number of barriers required in any given layer. Satisfactory performance is obtained from the unit when the following equations concerning the number of barriers per layer are satisfied:

$$S_N \leq 2 \frac{[2N-3-(-1)^N]}{4} \quad (3)$$

wherein S_N is the number of barriers in the last, or lowermost, layer and N is the total number of layers, and

$$S_n \geq \frac{2n+1-(-1)^n}{4} \quad (4)$$

wherein S_n is the number of barriers in any given layer except the last layer and n is the number of the given layer ($n \neq N$). The following table shows some of those values which satisfy Equations 3 and 4.

$n(N)$	$S_N \leq$ (Eq. 3)	$S_n \geq$ (Eq. 4)
1	1	1
2	1	1
3	2	2
4	2	2
5	4	3
6	4	3
7	8	4
8	8	4
9	16	5
10	16	5

¹ These values of course are eliminated by the requirements of the construction of the unit.

The number of barriers in the two lowermost layers and the proximity of the parallel barriers in all layers directly determine the number of finish points on the base of the unit. For example, taking the simplest case meeting the requirements of the present invention, i.e. six barriers in four layers, it can be seen that there will be four points at which the two barriers in the lowermost layer cross the two barriers in the immediately adjacent layer. For each cross point, the detonation is diverted four ways, the detonation being split into two segments upon arrival at the upper of the two barriers of the cross point, each of the two segments being split in two at arrival at the lower of the two barriers. In the case of the FIGURE 1 embodiment wherein the adjacent barriers of each layer are sufficiently separated to provide a cross-sectional area of explosive sufficient to provide two detonation paths between every two parallel barriers, four finish points result from every cross point. Therefore, in the FIGURE 1 embodiment having four cross points, the detonation ultimately arrives at sixteen finish points. In the unit of FIGURE 1 as shown, there are 64 points at which the barriers in the lower two layers cross, giving 64×4 , or 256, finish points. In the unit of FIGURE 2, however, the barriers in each layer are so close that the cross-sectional area between adjacent parallel barriers provides

only one detonation path, thus, one detonation segment of each pair between adjacent parallel barriers is cancelled out. Therefore, a FIGURE 2 unit having six barriers will have nine finish points. In the unit of FIGURE 2 as shown, there are a total of 56 cross points in the designated layers and 72 finish points on the base, the number of finish points on the base being related to the number of barriers in the two lowermost layers in the following manner:

$$P_f = (x+1)(y+1) \quad (5)$$

wherein P_f is the number of finish points, x is the number of barriers in one of the two lowermost layers, and y is the number of barriers in the other of the two lowermost layers. This feature, i.e. the number of finish points on

15 the base, imposes another factor which must be considered in the design of a unit for a specific application. For certain applications, only nine finish points would be required and the FIGURE 2 surface wave generator of simplest configuration would be suitable. However, in 20 other applications, more finish points are necessary and the use of the FIGURE 1 unit or units having more barriers is required.

Inasmuch as the number of finish points per unit of area of the base of the device is related to the number 25 of cross points and thus the number of barriers per unit area, control over the number of finish points per unit area may be afforded by regulation of the size of the barriers. When only a few finish points, for example nine or slightly more, on a large surface area are required, the 30 barriers used are relatively large in size and close together within layers. To increase the number of finish points on the same area, the size of the barriers is reduced and if desired the gap between barriers within the layer is increased. A large number of finish points on a small area 35 may be provided by using very small barriers, for example those having a cross-sectional area of only three square millimeters when such cross-sectional area is sufficient to prevent propagation of the detonation through the barrier as determined by the specific explosive composition and barrier material used.

As afore-mentioned, the initiation point-finish point paths must be of sufficient cross-sectional area to support the detonation. Since the exact cross-sectional area of the explosive train required for support of the detonation 45 is a direct function of the specific explosive used, no exact value for the specific cross-sectional area required can possibly be set forth. However, I have found that the cross-sectional area of an explosive train of a very sensitive explosive is sufficient to support the detonation when 50 the explosive material fills a gap of 0.3 millimeter between adjacent barriers in any layer containing more than one barrier, i.e. when the explosive train has a width of 0.3 millimeter, the thickness of the barrier regulating the thickness of the explosive train and any thickness of barrier sufficient to prevent propagation of the detonation therethrough providing sufficient thickness of this sensitive explosive when the train width is 0.3 millimeter to provide sufficient cross-sectional area for support for detonation. Therefore, I may state that the gaps between barriers 55 should have a minimum width of 0.3 millimeter.

60 Either a solid inert material or air is suitable for use as the rod-shaped barrier. There exists a large variety of solid substances from which the specific material used in the barriers may be chosen from the viewpoints of economy, availability, ease of handling and the like. Such substances include metals such as lead, rubber, plastic, glass, wood, and so forth.

65 Although the invention has been described in detail in the foregoing, it will be apparent to those skilled in the art that many variations are possible without departure from the scope of the invention. I intend, therefore, to be limited only by the following claims.

I claim:

70 1. A surface wave generator wherein the natural detonation front is distorted to arrive simultaneously at a

plurality of finish points on a surface which consists of a mass of a cap-sensitive high explosive within which mass are disposed at least six inert rod-shaped barriers each of which barriers extends from a surface of said mass to another surface of said mass, said barriers defining a continuous matrix of said explosive and delimiting a series of paths from an initiation point to each of said finish points, each of said paths being of sufficient cross-sectional area to support the detonation, the shortest path from said initiation point to any one finish point being substantially equal to the shortest path from said initiation point to any other finish point, said barriers being stacked in at least four parallel layers, the barriers in each of said layers being parallel, coplanar, and separated by a gap of at least 0.3 millimeter, the barriers in each of said layers crossing perpendicularly the barriers in the immediately adjacent layers and lying directly over the gaps between barriers in the next-to-nearest lower layer, each of said barriers having a cross-sectional area of at least 3 square millimeters and sufficient to prevent the propagation of the detonation through the barrier, the minimum dimension of any barrier being at least 1 millimeter, the length of the barrier in any given layer except the last layer being equal to at least

$$\left(\frac{2n+1-(-1)^n}{4} \right) W_{n-1}$$

wherein n is the layer number and W_{n-1} is the width of each individual barrier in the preceding layer, the length of the barrier in the last layer being equal to at least

$$\left(\frac{\frac{1}{2}N-1+(-1)^N}{4} \right) W_{N-1}$$

wherein N is the total number of barrier layers and W_{N-1} is the width of each individual barrier in the next-to-last layer, the number of barriers in any given layer except the last layer being equal to at least

$$\frac{2n+1-(-1)^n}{4}$$

wherein n is the layer number, the number of barriers in the last layer being equal to at most

$$\frac{[2N-3-(-1)^N]}{2}$$

15 wherein N is the total number of barrier layers.

2. A surface wave generator according to claim 1, wherein the barriers of maximum width are located in the two uppermost layers, the barriers decreasing in width with increase in their number per layer.

20 3. A surface wave generator according to claim 1, wherein all barriers are of identical width.
